UNITED STATES PATENT OFFICE

FRANK B. WENTWORTH, OF INDEPENDENCE, KANSAS.

TANK.

No. 880,846.

Specification of Letters Patent.

Patented March 3, 1908.

Application filed April 19, 1906. Serial No. 312,694.

To all whom it may concern:

Be it known that I, FRANK B. WENTWORTH, a citizen of the United States, and resident of Independence, county of Montgomery, and State of Kansas, have invented 5 certain new and useful Improvements in Tanks, of which the following is a specification, and which are illustrated in the accompanying drawings, forming a part thereof.

10 The invention relates to tanks of sheet metal, and particularly to those which are of generally cylindrical shape and have walls composed of a plurality of sections.

15 The invention has for its object to provide simple and efficient means for uniting the several sections of the walls of the tank of the kind described, and to increase the strength and stiffness of such tanks, thereby rendering them less likely to become indented or mis- 20 shapen by rough handling or in transportation from place to place.

The invention is exemplified in the structure hereinafter described and illustrated in the accompanying drawings, in which—

25 Figure 1 is an elevation, partly in section, of a tank constructed in accordance with the invention; and Figs. 2, 3 and 4 are sectional details of the same drawn to a larger scale.

30 The invention is applicable to sheet metal tanks of various forms.

In the drawings is shown a cistern for the storage of liquids which, in practice, will usually be of moderate size. Its walls are preferably of a heavy grade of galvanized 35 iron and formed in sections, 10, 11, 12, 13 and 14, one of these sections, as 10, being of the proper shape to provide a bottom for the tank, while another, as 14, may form a dome-shaped or conical top having a filling opening 40 15. The remaining sections, 11, 12 and 13, as shown, are cylindrical in form and compose the body wall of the tank.

45 In carrying out the invention there is provided a plurality of metal bands or hoops 16 of channel section, each preferably having its flanges 17, 18, directed outwardly. These hoops are most conveniently formed by bending a strip of channel iron to a circle and uniting the ends in any convenient manner, 50 as by means of a tie plate 25 and rivets 26. Preferably the hoops 16 are of galvanized material and one of them is employed for

uniting each of the sections of the tank with the next adjacent section. In forming this connection the hoop member is, as shown, 55 placed within the tank and the meeting edges of the tank sections are flanged inwardly, as indicated at 19, 20, Figs. 3 and 4 of the drawings, the flanges being then fitted into the groove of the hoop member 16 60 and bound in position by means of a band 21 preferably of round iron or stout wire. If desired the joints thus formed may be "sweated" or "calked" with solder. As shown a liberal amount of soldering material 65 22 is applied about the binding member 21, to give the joint a smooth or finished appearance, while some of this solder is soaked or sweated into the joint to unite the flanged edges 19, 20, of the tank sections with the 70 web of the hoop member 16, as indicated at 23, thus forming a perfectly water-tight connection.

In the form of tank shown in the drawing, the rim of the filling opening 15 is strengthened by a tubular hoop 24, to which the edges of the upper section 14 of the tank are fitted and united by screw-bolts 27.

By the improvement herein shown and described, there is provided a sheet metal tank 80 of great durability and strength, as the hoop members 16 serve not only as a convenient means for uniting the several sections of the tank but also effectively resist various forms of rough usage to which it may be subjected and which might otherwise seriously distort or puncture its walls.

I claim as my invention—

In a tank having sectional walls of sheet metal in combination, a circumferential 90 hoop of channel section having its flanges directed outwardly, contiguous edges of adjacent wall sections of the tank being flanged inwardly and laid in the groove of the channel, a band surrounding the tank and bearing upon the edges of the wall sections within the groove, and a calking of solder for the joint thus formed, the solder being applied over the band.

FRANK B. WENTWORTH.
